UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC GANG-FITTING.

1,133,197.

Specification of Letters Patent. Patented Mar. 23, 1915.

Application filed August 25, 1914. Serial No. 858,541.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Gang-Fitting, of which the following is a specification.

My invention relates to electric gang fittings and particularly to switch gangs, and the object of my invention is to provide a compact installation for a plurality of independent switch units.

In the accompanying drawings, Figure 1 15 is a broken side elevation of a switch gang in which my invention is embodied in one form; Fig. 2 is a plan thereof with the cover plate removed and one of the switches removed; and Fig. 3 is a perspective of the 20 carrying frame shown in Figs. 1 and 2.

The present invention is particularly designed for use in positions in which the available room for the installation is limited and narrow, such for instance as the dressing 25 room of a Pullman car. Only extremely narrow panels are here available for the switch gang installation which sometimes numbers as many as eight switches in the gang. Obviously compactness and neat appearance are essential in an installation of 30 this character. Moreover, it is extremely desirable to have the switches available for independent removal for repair or renewal, since the vibration of the car is apt to cause 35 defects, and it is extremely simple and convenient, as well as inexpensive, to handle each switch unit separately in case of trouble.

The switch gang here shown is carried on 40 a suspension frame or bridge piece 10 having end flanges 11 with ears 12 to overlie the support 13 which may be the inner wall of a metal car, cut away to afford a recess for the switch gang, and punched at 14 to 45 permit the passage of the screw bolts 15 therethrough. The ears 12 may be offset at 16 and tapped to receive the screws 17 of the face plate 18. The several switch units 19 are supported upon the bridge piece 10 by 50 screws 20 which pass downward through the insulating bodies and take into taps 21. To space the wire terminals 22 as far apart as possible and still afford wiring room, the porcelain bodies of the switches are trape-

zoidally shaped, and the corners 23 on the 55 long axis of the trapezoid cut off or flattened to permit the passage to the terminals of the wires which are led thereto through marginal recesses or apertures in the base of the frame. Lateral support for the switch 60 bases is afforded by flanges, such as 24, struck up from the frame base. Where these flanges are given the form of continuous longitudinal side bars, they also impart added rigidity to the structure as a whole. 65 The switch spindles 25 pass up through the face plate 18 and receive the operating thumb pieces 26 threaded thereon. The switch mechanism, *per se*, is of common construction.

The compactness of assembly of the independent switch units, the light supporting frame, the convenient wiring of the switch terminals and the ready accessibility of the 70 separate units for repair or replacement, which result from the novel construction specified, present advantages, the novelty and value of which are readily recognized.

I claim as my invention:—

1. A gang fitting of the type described, 80 comprising a suspension frame having end pieces and lugs thereon for mounting the frame on a suitable support, in combination with a plurality of independent electrical units having insulating bodies of like shape 85 mounted on the base of said frame, wire terminals on each of said units and recesses at the opposite margins of the base of the frame and adjacent each of said units for admitting leading-in wires to said terminals, together with marginal flanges on said base affording lateral support for said units.

2. A gang fitting of the type described, comprising a suspension frame having end pieces and lugs thereon for mounting the 95 frame on a suitable support, in combination with a plurality of independent electrical units having insulating bodies of like shape mounted on the base of said frame, wire terminals on each of said units and recesses 100 at the opposite margins of the base of the frame and adjacent each of said units for admitting leading-in wires to said terminals, together with marginal flanges in the form of longitudinal strengthening bars affording lateral support for said units.

3. A gang fitting of the type described, comprising a suspension frame of generally

- trapezoidal shape in plan, end pieces thereon having lugs for mounting the frame on a suitable support, in combination with a plurality of independent electrical units
- 5 having insulating bodies of generally trapezoidal shape mounted side by side longitudinally of said frame, and relatively low marginal flanges struck up from the opposite sides of the frame base and engaging the
- 10 units to afford lateral support thereto.
4. A gang fitting of the type described, comprising a suspension frame of generally trapezoidal shape in plan, end pieces thereon having lugs for mounting the frame on a
- 15 suitable support, in combination with a plurality of independent electrical units having insulating bodies of generally trapezoidal shape mounted side by side longitudinally of said frame, together with a rectangular
- 20 face plate overlying said fitting and secured to said supporting lugs, substantially as described.

5. A gang fitting of the type described, comprising a suspension frame having end uprights with lugs for mounting the frame on a suitable support, in combination with a plurality of independent electrical units having insulating bodies of generally trapezoidal shape with their corners flattened on the longer axis, juxtaposed on the base 25 of said frame, wire terminals on each of said fittings, and marginal recesses on opposite sides of the base of the frame to admit leading-in wires, the space between said flattened corners and the side of the adjacent unit serving to form a wire channel, 30 substantially as described.

In testimony whereof I have signed my name to this specification, in the presence of two subscribing witnesses.

GEORGE B. THOMAS.
